PROCESS FOR THE PRODUCTION OF SULPHO-ACIDS FROM HYDROCARBON OILS

No Drawing. Application filed December 30, 1925, Serial No. 78,486, and in Germany January 26, 1925.

This invention relates to processes for the production of sulpho-acids from hydrocarbons and it comprises a process in which a hydrocarbon oil which may no longer be sulfonated is oxidized with air to dehydrogenate the oil and the oxidized mixture thereafter sulfonated with sulphuric acid.

In the sulfonation of crude petroleum hydrocarbons such as naphtha, naphtha distillate, etc., sulfonation may be carried out up to a certain point beyond which no more sulfonation takes place, even though the sulfonating mixture is heated to temperatures of 100° C. On this fact is based the process for the production of the so called white oils, which are both odorless and tasteless and are known under the name of "parafinum liquidum," or liquid paraffine. These oils are usually prepared by sulfonating heavy solar, spindle, or machine oil distillates by means of 40 to 50% fuming sulphuric acid. A yield of 50 to 60% of white oils are obtained which consist of a mixture of hydrocarbons. Further sulfonation of these hydrocarbons is 25 very difficult to bring about.

The object of the present invention is to devise a process wherein the white oils, which normally resist further sulfonation, may be converted into sulfonic acids. We have found that these white oils can be oxidized by blowing air or oxygen through them. The resulting oxidized product, may be then sulfonated easily with concentrated sulphuric acids. The sulpho-acids which are formed 35 thereby are separated from the sulphuric acid and unchanged hydrocarbons in the usual way.

The oxidation of the white oils is so regulated that only a dehydrogenation takes place. While these white oils may be oxidized to obtain high molecular weight fatty acids, usually in the presence of catalysts and high pressures, we restrict our oxidation merely to a dehydrogenation of the oil. 45 Therefore we carry out our oxidation process at comparatively low temperature, 140 to 180° C. being sufficient and under atmospheric pressure and in the absence of catalysts. Furthermore, the oxidation must be stopped as soon as fatty acids begin to form. The quan-

tity of fatty acids in the oxidized oil should not exceed 5 to 10%.

As stated, after the oil has been oxidized to dehydrogenate it, it is again treated with sulphuric acid.

55

Example 1

100 parts of a crude petroleum distillate, having a specific gravity of 0.898 and which has been purified with 50% of fuming sulphuric acid containing 20% sulphuric acid anhydride and subsequently washed, is treated with air at a temperature of 140 to 150° C. until about 5% of fatty acids are formed. 60 100 parts of the thick, dark, yellow oil, resulting from the oxidation is then sulfonated with 100 parts of concentrated sulphuric acid having a specific gravity of 1.82. The sulfonation is carried out at a temperature of about 60 to 70° C. and the sulphuric acid is 65 slowly poured into the oil with rapid agitation. The mixture is then allowed to stand and from it about 35% of sulfonic acid derivatives are obtained, 50% of unchanged oil 70 being separated off.

75

Example 2

A spindle oil distillate is oxidized by blowing moist air through it at a temperature of 150 to 160° C. until about 10.5% fatty acids 80 are formed. 100 parts of the oxidized oil is then mixed with 50 parts of sulphuric acid having a specific gravity of 1.82. About 30% of sulfonic acids are obtained from the sulphuric acid layer and about 3% of sulfonic 85 acids are obtained from the upper oily layer after the mixture has been allowed to stand and stratify.

In general, particularly good yields of sulfonic acids may be obtained when the oxidized 90 hydrocarbon oil contains about 5% of fatty acids.

The sulfonic acids are extracted from the unchanged oil in the usual way, for instance, by treating with an alkaline solution, extraction with aqueous alcohol, etc. They may be extracted in the form of salts of heavy metals insoluble in water or in various solvents such as benzine, petroleum, benzol, etc.

The remaining unchanged oil can again 100

be oxidized and sulfonated as described so that eventually all of the oil is converted into sulfonic acids.

5 The sulpho-acids so obtained may be used in the hydrolysis of fats, as emulsifying agents, in the textile industries to wash wool, etc.

What we claim is:

10 1. The process of preparing sulpho-acids from crude petroleum distillates no longer susceptible to sulfonation which comprises dehydrogenating the crude petroleum distillate by treatment with air and thereafter sulfonating the oil.

15 2. The process of preparing sulpho-acids from hydrocarbon oils no longer susceptible to sulfonation which comprises oxidizing the hydrocarbon oils by blowing air therethrough and thereafter sulfonating the oxidation product with strong sulphuric acid.

20 3. The process of producing sulpho-acids from hydrocarbon oils no longer susceptible to sulfonation which comprises oxidizing the oils by blowing air therethrough until a small 25 amount of fatty acids are formed in said oils and thereafter sulfonating the oxidation product.

25 4. The process of producing sulpho-acids from hydrocarbon oils no longer susceptible to sulfonation which comprises oxidizing the hydrocarbon oils by blowing air therethrough, sulfonating the oxidation product, separating sulpho compounds from the unchanged hydrocarbons and again sulfonating 35 the oxidation product.

5. The process of preparing sulpho-acids from crude petroleum distillates which have been treated with strong sulphuric acid and no longer may be sulfonated, which comprises oxidizing the distillate by blowing air therethrough and thereafter sulfonating the oxidation product.

45 6. The process of preparing sulpho-acids from crude petroleum distillates which have been treated with sulphuric acids and may no longer be sulfonated which comprises oxidizing the distillate with air until about 5% of fatty acids are formed and thereafter sulfonating the oxidation product.

50 In testimony whereof we affix our signatures.

GRIGORI PETROFF.
